UNITED STATES PATENT OFFICE.

CHARLES A. DORN, OF CANTON, OHIO, ASSIGNOR TO THE BONNOT COMPANY, OF CANTON, OHIO, A CORPORATION OF OHIO.

TILE CUTTING AND DELIVERING MACHINE.

1,162,284.

Specification of Letters Patent.

Patented Nov. 30, 1915.

Application filed November 8, 1913. Serial No. 799,865.

To all whom it may concern:

Be it known that I, CHARLES A. DORN, a citizen of the United States, residing at Canton, in the county of Stark and State of Ohio, have invented new and useful Improvements in Tile Cutting and Delivering Machines, of which the following is a specification.

The invention relates to machines for cutting a column of clay into suitable lengths for bricks or tiles, and especially to machines which cut the column into sections having a longer length than width or depth, as in the usual manner of making hollow blocks and drain tiles; and the object of the improvement is to provide a sectional conveyer in such a machine, which will separate the severed blocks or tile at the forward or discharge end of the machine, and automatically deliver them on end upon a receiving conveyer, traveling faster than the sectional conveyer, so that the upright blocks or tiles will be spaced widely apart on the receiving conveyer and can be readily grasped and removed therefrom by a plurality of workmen.

When a column of clay is cut into lengths for making blocks or tiles in the usual manner on a sectional conveyer, the severed ends are so close together that the blocks or tiles can only be removed, one at a time, from the forward end of the series; and the prone position of the product renders it difficult to grasp and then remove the tile by manual means, for standing them upright upon a rack for drying. These difficulties are overcome by the present invention in which a receiving conveyer is located at the forward end of the sectional conveyer of the cutting machine, to receive the blocks or tiles as the same are delivered thereby; and the sectional conveyer is provided with mechanism by means of which each block or tile at the forward end of the severed series is first slightly tilted and separated from the next succeeding block or tile, and then quickly carried and rotated from the prone to an upright position, and squarely seated on its lower severed end upon the receiving conveyer, without mutilating the end or distorting the body of the block or tile.

Further features of the invention relate to the devices employed for controlling the movements of the tile carriers of the cutting

machine conveyer, so that the same will clear the receiving conveyer and the severed blocks or tiles which have been delivered upon the same, and will also clear the column of clay as the same is received at 60 the rear end of the cutting machine.

When applied to a tile cutting machine, the invention may be embodied in the form illustrated in the accompanying drawings, forming part hereof, in which,

Figure 1 is an outline side elevation of a tile cutting machine with a receiving conveyer at the forward end thereof, showing the general arrangement of the parts involved in the improvement; Fig. 2 is a longitudinal sectional elevation of the tile cutting machine, showing the rear end of the receiving conveyer at the front end thereof; Fig. 3 is a fragmentary sectional view of the forward end of the tile cutting machine, 70 and the rear end of the receiving conveyer, showing the relation of the parts immediately after one tile has been delivered, and showing the preliminary separation of the remaining forward tile from the next succeeding tile of the severed series; Fig. 4 is a similar view showing the secondary tilting and dropping movement of the forward tile; Fig. 5 is a similar view showing the final turning of the tile into an upright position, and the seating of its lower end squarely upon the conveyer belt; Fig. 6 is a fragmentary longitudinal section of the rear end of the cutting machine, showing one tile carrier rising to pass under the clay 90 column; Fig. 7 is a similar view showing the tile carrier passing under the clay column; Fig. 8 is a similar view showing one tile carrier raised upward against the under side of the clay column, and the next succeeding carrier rising around the rear end of the cutting machine; Fig. 9 is a longitudinal section of the forward and rear ends of the cutting machine showing details of the controlling devices for the tile carriers; Fig. 10 is a rear end view of the cutting machine with the parts substantially as shown in Fig. 9; Fig. 11 is a transverse section of the forward end of the cutting machine substantially as on line 11—11, Fig. 9; Fig. 12 is a fragmentary perspective view looking upward under one tile carrier at the beginning of its delivering movement as illustrated in Fig. 3; Fig. 13 is a detached perspective view of one tile carrier; and Fig. 14 is a 110

fragmentary perspective view of the supplemental cam track in the rear end of the cutting machine.

Similar numerals refer to similar parts throughout the drawings.

The frame of the cutting machine includes the side plates 1, mounted on the legs 2, and provided on the inner side with the tracks or ways 3 for the wheels 4 of the sections 5 and 5^a forming endless chains on each side of the conveyer, to which chains are pivoted the series of tile carriers 6 thus forming a sectional conveyer for the cutting machine, the same being provided with cutting mechanism 7 of any well known construction and operation; and as shown, the cutting mechanism includes a series of radial arms 8 on each side of the machine, the ends of which are guided between the adjacent ends of the tile carriers 6 by the standards 9 formed on certain sections 5 of the carrier chains in a manner well known in the art.

For the purposes of the present invention each tile carrier 6 is composed of a suitable bottom plate 10 upon which is formed or secured a suitable rest for the particular cross section of the clay column, which may be a flat plate 11 when the clay column is rectangular as for making hollow block, or the curved trough 12 when the clay column 13 is round, as shown, for making cylindric tiles 14; which trough may be provided with suitable adjusting devices 15 in the usual manner for fitting clay columns of different diameters.

The tile carriers 6 correspond in length to two sections 5 and 5^a of the conveyer chains; and each carrier is pivotally connected between the chains to the forward section 5 of each pair by means of the journal bearings 16 on the under side of each forward portion of the bottom plate 10 of the carrier, and the pivot posts 17 extending inward from the middle portion of each chain section 5. The width of the carrier is less than the clear space between the conveyer chains, so that the rear or heel end of the carrier may swing freely between the chains upon its pivotal bearings 16.

The forward chain sections 5 are connected by the cross bar 18, which serves not only for the purpose of properly spacing the conveyer chains apart, but as an abutment for the forward end of the corresponding tile carrier, and stops the rotation of the same inward between the chains and prevents the heel end of the carrier from dropping downward during the return movement of the chains in the under side of the machine.

One or more, two as shown, longitudinal supporting tracks 19 are provided in the upper portion of the cutting machine, intermediate the side plates thereof, which tracks 65 may be formed by the upper edges of plates

20 properly positioned in the machine; and the under side of the rear heel ends of the tile carrier bottom plates are provided with corresponding rollers 21 which travel on the tracks 19 during the forward movement of the carriers in the upper portion of the cutting machine; and these tracks and rollers are so positioned that each tile carrier will be held in true horizontal position, and in proper alinement with each other, to form a continuous coplanar support for the clay column 13, during such forward movement.

At the forward end of the machine, the tracks 19 are continued to form the cam tracks 22, which first drop abruptly downward and then curve gradually forward to a point near the center or axis of the curved forward ends of the ways 3; thence the cam tracks 22 curve abruptly downward and rearward and then more gradually rearward to a point adjacent to the line of the ways 3 and approximately below the abrupt downward beginning of the cam tracks.

On one side, preferably the inner side, of one or both of the cam tracks 22, is provided the cam flange 23, the upper end 24 of which flange is located on the upper side of the abrupt convex curve, which may be called the nose of the cam track, and the lower end 25 of which flange terminates at the lower rear end of the track.

The bottom plate 10 of each tile carrier is provided, on its under side, with the downwardly protruding L-shaped clip or finger 26 which is adapted to engage the cam flange 23 for controlling the movements of the rear end of the carrier when it has been rotated to and beyond an upright position in passing downward around the forward end of the cutting machine, in the operation of delivering a tile upon the rear end of the receiving conveyer 27, which rear end is located under the forward end of the cutting machine. The engagement of the L finger 26 with the cam flange 23 also serves to hold the rear end of the tile carrier upward so that it will clear above the rear end of the receiving conveyer, until the heel end of the carrier has passed downward and rearward beyond the receiving conveyer; whereupon the L finger drops off the rear end 25 of the cam flange and the heel end of the carrier drops downward until the toe end thereof is stopped by the abutment bar 18 which connects the conveyer chain sections 5.

In the operation of the cutting machine, the clay column 13 is severed by the cutting mechanism 7 into suitable lengths for making the tiles 14 in the manner well known in the art; said sections being substantially equal in length to the tile carrier upon which it is located. When the forward wheels 4 of the forward chain sections 5 to which the forward end portion of the carrier is pivoted, begins to descend around the for

ward curves of the ways 3, as shown in Fig. 3, it is evident that the forward end of the carrier will be tilted slightly downward with reference to the rear end, which continues to be supported on the horizontal track 19; thereby slightly separating the rear end of the one carrier from the rear end of the next succeeding carrier, and considerably separating the adjacent severed ends of the tiles, as shown in Fig. 3. When the pivot bearings 16 of the carrier continues downward about half way around the curved way on the forward end of the cutting machine, the parts are so arranged that the rollers 21 on the heel end of the carrier will ride downward upon the concavely curved portion of the cam track 22, beginning as shown in Fig. 4, and continuing until the bottom plate of the carrier strikes the upper side of the abrupt nose of the cam track, as shown in Fig. 9; in which relation of the parts, the carrier is preferably positioned at an inclination of something less than 45° from horizontal, so that there is no tendency for the tile to slide forward upon the carrier. When the pivot bearings 16 of the carrier continue downward and rearward in the orbit described by the conveyer chains, the middle portion of the bottom 30 plate of the carrier swings or rotates around the noses of the cam tracks 22 as fulcrums, thereby swinging the carrier and gyrating the tile thereon substantially on its center into an upright position and delivering the forward end of the tile squarely upon the rear end of the receiving conveyer 27, which is properly positioned to receive the same, as shown in Fig. 5, and by broken lines with reference to the tile 14 and its carrier 6 in Fig. 9.

As it is preferred to deliver the tile upon the receiving conveyer at a slight interval before the tile is rotated into vertical position, so that the momentum of the tile resulting from its downward and slightly forward movement will coincide with its axis; it is accordingly preferred to slightly incline the rear portion of the receiving conveyer to a corresponding degree as shown in the several views. It being understood that the receiving conveyer is gradually curved forward into a horizontal plane, as shown in Fig. 1.

The receiving conveyer 27 is geared to operate at such a speed, preferably somewhat more rapid than the speed of the chain conveyer, so that when a tile is delivered upon its rear end, the tile will at once be moved forward to clear the heel end of the carrier, which in turn is carried directly downward and rearward, clear of the receiving conveyer by the controlling cam flange, as shown in Figs. 1 and 3.

The bottom plates 10 of the tile carriers are also provided at or near the middle on

the under side with the supplemental roller 28, and the rear end of the cutting machine is provided with the supplemental curved cam track 29 for swinging the carrier into proper position for rising under the clay column, as the conveyer chains are carried by the ways 3 upward in an orbit around the rear end of the cutting machine. At the beginning of this movement, the heel end of the carrier hangs downward as the front end thereof is stopped by the bar 18 until the chain brackets 5 continue upward around the end of the cutting machine far enough to withdraw the stop bar 18 from the forward end of the carrier; whereupon the supplemental roller 28, contacts with the supplemental cam track 29 and swings the heel end of the carrier rearward and upward upon the pivotal bearings 16 thereby gyrating the carrier so that its toe end will clear the clay column 13 in moving upward thereunder, as shown successively in Figs. 8, 6, 7 and 9.

The supplemental cam track 29 is continued horizontally forward at its upper end for a short distance, in such a plane that the supplemental roller 28 traveling thereon will elevate the tile carrier upward into full contact with the lower side of the clay column 13; the track 29 being continued forward far enough to support the supplemental roller 28 until the rollers 21 at the heel end of the carrier ride upon the horizontal portion of the supporting tracks 19, after which the supplemental roller 28 remains idle until the carrier travels around the forward end and returns to the rear end of the cutting machine.

To those skilled in the art in making machines of the class described, many variations in construction and widely differing embodiments and applications of the invention will suggest themselves, without departing from the spirit and scope of the claims; the disclosure and the description herein are purely illustrative and are not intended to be in any sense limited.

I claim:

1. A machine for cutting tile and the like including a conveyer having carriers pivoted thereto, a receiving conveyer at the forward end of the cutter conveyer, and cam devices at the forward end of the cutter conveyer for first tilting the carriers and then bodily dropping them downward, and then swinging the carriers to gyrate the tile and deliver them in upright position upon the receiving conveyer.

2. A machine for cutting tile and the like including a conveyer having carriers pivoted thereto, a receiving conveyer at the forward end of the cutter conveyer, and cam devices at the forward end of the cutter conveyer for first tilting the carriers and then bodily dropping them downward, and then

swinging the carriers to gyrate the tile and deliver them in upright position on the receiving conveyer, the receiving conveyer having its rear end inclined to squarely receive the forward end of the tile.

3. A machine for cutting tile and the like including a frame with conveyer chains therein, carriers each pivoted intermediate the middle and forward end to the chains and having an L finger in the middle portion of its under side, a longitudinal track for supporting the rear ends of the carriers coplanar in the upper portion of the frame, a cam track guiding the rear end of each carrier downward as its forward end descends at the forward end of the machine, a cam nose forming a fulcrum for the middle of each carrier as its forward end continues downward and rearward, a cam flange engaging and guiding the L finger during the downward rearward movement of the carrier, and a stop holding the rear end of the carrier from rotating outward along the bottom of the frame.
- 10 4. A machine for cutting tile and the like including a frame with conveyer chains therein, carriers each pivoted intermediate the middle and forward end to the chains and having an L finger in the middle portion of its under side, a longitudinal track for supporting the rear ends of the carriers coplanar in the upper portion of the frame, a cam track guiding the rear end of each carrier downward as its forward end descends at the forward end of the machine, a cam nose forming a fulcrum for the middle of each carrier as its forward end continues downward and rearward, and a cam flange engaging and guiding the L finger during the downward rearward movement of the carrier.
- 15 5. A machine for cutting tile and the like including a frame with conveyer chains therein, carriers pivoted forward of their centers to the chains, and cam devices at the forward end of the frame for first tilting the carriers and then bodily dropping them downward, and then swinging the carriers to gyrate the tile and deliver them in upright position.

- 20 6. A machine for cutting tile and the like including a frame with conveyer chains therein, carriers pivoted forward of their centers to the chains, a longitudinal track for supporting the carriers in the same plane in the upper portion of the frame, stops holding the rear ends of the carriers from swinging downward in the lower portion of the frame, and a cam track guiding the rear end of the carriers to swing rearward and upward upon their pivots when passing around the rear end of the machine.
- 25 7. A machine for cutting tile and the like including a frame with conveyer chains therein, carriers pivoted forward of their centers to the chains, a longitudinal track for supporting the carriers in the same plane in the upper portion of the frame, and a cam track guiding the rear end of the carriers to swing rearward and upward when passing around the rear end of the machine.
- 30 8. A machine for cutting tile and the like including endless chains, ways guiding the chain downward and rearward at the delivery end of the machine, carriers pivoted to the chains and cam devices at the forward end of the conveyer for first tilting the carriers and then bodily dropping them downward, and then swinging the carriers to gyrate the tile and deliver them in upright position.

- 35 9. A machine for cutting tile and the like including a conveyer, carriers pivoted to the conveyer, means guiding the conveyer in an orbit at the end of the machine, and means for gyrating the carriers on their pivots while moving in the orbit.

5. A machine for cutting tile and the like including a frame with conveyer chains therein, carriers pivoted forward of their

45 centers to the chains, and cam devices at the forward end of the frame for first tilting

Copies of this patent may be obtained for five cents each, by addressing the "Commissioner of Patents, Washington, D. C."
